C. H. Crawford ATTORNEY

UNITED STATES PATENT OFFICE.

TERESA M. WOOD, OF SPOKANE, WASHINGTON.

COMBINED FOLDING CUPBOARD AND TRANSPORTING CHEST.

Application filed October 25, 1926. Serial No. 144,049.

The object of this invention is to provide an article of furniture which is designed and constructed to perform the dual function of a kitchenette cupboard and a transporting chest.

My invention is of particular utility to that class of people, mostly single, who live in small or single apartments or rooms, and who provide themselves with meals on a small scale, and whose needs involve some form of chest for packing linen and cooking utensils and supplies while moving. Thus, my invention is particularly addressed to transients who frequently move from place to place.

The device of my invention provides what I will term a cupboard in which cooking supplies and utensils may be disposed in the manner to be later described, the device affording a work board and a subjacent container or chest for the less frequently employed articles such as linen.

Now it is a feature of my invention to embody these elements in a folding structure that is designed to be disposed in an upright position when employed as a cupboard, and which is adapted to be folded in such a manner, and by reason of its novel construction, so as to form a transporting chest in which the contents may be shipped as in a trunk.

It is a feature of my invention to employ folding sections of the same height and width so that when the sections are folded together, they will form a transporting chest in which all the outside walls will be flush, irrespective of the depth of the sections.

It is a further feature of my invention to provide the sections with closures adapted to perform various independent and interdependent functions in the different positions to which they may be adjusted.

My invention has many other features and objects which will be more fully described in connection with the accompanying drawings and which will be more particularly pointed out in and by the appended claims.

50 In the drawings:

Fig. 1, is a front elevation of the cupboard structure in an upright position and with the closures in a closed position.

Fig. 2, is a front elevation thereof with the closures in an open adjustment.

Fig. 3, is a vertical sectional view on line 3—3 of Fig. 2.

Fig. 4, is a view in side elevation with the closures in an opened adjustment.

Fig. 5, is a rear fragmentary view looking in the direction of the arrow in Fig. 3.

Fig. 6, is a horizontal sectional view on line 6—6 of Fig. 3.

Fig. 7, is a view in side elevation showing how the sections are folded to form a chest.

Fig. 8, is a fragmentary view looking in the direction of the arrow of Fig. 7 showing the sections locked together.

Like characters of reference designate similar parts throughout the different figures of the drawings.

The device of my invention includes what I will term a chest section and a cupboard section, and I will first describe the former in detail, and then the latter, and finally, the interdependent coaction of the two.

Said chest section comprises a closed back wall 1 and closed side walls 2 and 3 and an open front face 4. Top and bottom walls are designated at 5 and 6, respectively. Any desirable arrangement of shelves 7 and 8, may be provided and it may be stated that the chest section is especially adapted for linens and may also be used for dishes, when the device is in a cupboard service adjustment.

When the device is folded into a transporting chest, of course, the chest section may be used for anything that it is desired to pack therein. I provide the chest section, which is always the subjacent section, in this form of the invention, with means for closing the open front face. As shown, such means takes the form of door-like closures 9 and 10, which are preferably

jointly coextensive with the open front face so that when they are closed, they will conceal the front edge portions of the walls 1, 2, 3, 5 and 6, thereby simulating a cabinet

form of furniture unit. I have shown the closures 9 and 10 hinged to the side walls 2 and 3, by hinges 11 and 12. Means, such as a hook and stud device, 13 and 14, respectively, is employed to lock the closures 9 and 10, in a closed position, which means is disposed on the outside faces of said closures.

I have provided said closures with means on their inside faces whereby said closures may perform a function which will be later described.

I will next refer to the cupboard section

110

which is superimposed upon the chest section.

The cupboard section is provided with a back wall 15, side walls 16 and 17, a top wall 18 and a bottom wall 19. Thus, it will be seen that the cupboard section has closed rear and side faces and an open front face 20, the same as the subjacent chest section.

10 At this point I wish to emphasize an important feature which consists in providing these two sections of uniform size whereby they may be folded, as will hereinafter be described, and form a transporting chest 15 wherein all the outside walls will be flush.

I foldingly connect the sections by hinges 21 which are so disposed near the forward edges of walls 5 and 19 that the sections may be folded, as shown in Fig. 7, so that 20 the open front faces will be in abutting relation. In order to prevent relative movement between the sections when the latter are in the service adjustment shown in Fig. 3, I provide locking means for the rear portions 25 which may consist of the hook and stud 22 and 23, respectively, as shown in Fig. 5. This locking means, together with the hinges 21, serves to hold the sections rigidly in the upright position shown in Fig. 3.

30 The interior of the superimposed cupboard section is shown provided with shelves 24 and 25, on which suitable receivers 26 and 27, for cooking material may be disposed. A portion 28, of shelf 25 may be 35 used for cooking utensils. However, this shelving may be varied as conditions and trade requirements dictate.

I will next describe the improved closure means for the cupboard section.

40 In the present construction, I have shown upper and lower closures 29 and 30, the upper closure 29 being hinged at 31, to the outer edge of wall 18, and acting as an extension shelf when in the open position 45 shown in Fig. 3. A jointed support 32, is shown pivoted at 33, to wall 17, and at 34, to said closure, to hold the latter in a shelf forming open position, as shown. This support is capable of being broken at its joint 50 35, to allow the closure 29 to be closed, as shown in Fig. 1.

The closure 30, is also hinged at 36, to swing about a horizontal axis into the open position shown in Fig. 3, or into the closed 55 position shown in Fig. 1. In the latter position, the two closures are secured by means such as a hook 37 and stud 38, respectively, to entirely close the cupboard section. When the closure 30, is in the horizontal position 60 shown in Fig. 3, it functions as a work board, and also forms a flush extension with the top face of wall 19 whereby the usual mixing and other preparatory operations of the person doing the cooking, may be carried on. It will also be seen that the space 65

between wall 19 and the bottom of shelf 25, is ample for the temporary or other storage of utensils and materials.

I will next describe the novel coaction between the work board closure 30, and the 70 closure or closures 9 and 10.

Obviously, some form of support would be necessary and I employ either one or both of closures 9 and 10 in this capacity. It will be noted that these closures are high 75 enough to cover the edge of wall 5, therefore, when closure 30 is let down, it will rest on the top edges of closures 9 and 10 when the latter are in an open position. Thus, it will be seen that both the sections are accessible, as regards their interiors. I provide means in the form of simple slide bolt devices on the inner faces of closures 9 and 10, the same consisting of casings 39, in which bolts 40 are slidably disposed. 80 Notches 41, in the casings, permit of the bolt lugs 42 being shifted therein to lock the bolts in upper or lower positions. I provide the lower face of closure 30, with socket-like depression 43, into which the bolts 40 may be projected, to hold the closures, or one thereof, in the board supporting relation shown in Figs. 2 and 3. If it should be desired to unbolt one closure, to more readily gain access to the chest, this may be done, 85 as shown in Fig. 2, and still, the board 30 will be supported.

In order not to impose too much stress on the hinges 11 and 12, I arrange and proportion the closures 9 and 10 so that while their upper edges are coacting with closure 30 to support the latter, the lower edges 9' and 10' coact with the floor so that no strain will be imposed on the hinges. This coaction of the closures 9 and 10 with the floor, 105 performs another function in that they serve to stabilize the structure when the latter is in the service position shown in Fig. 3. Thus, I do not suffer any disadvantage in making the two sections of the same size, as 110 regards over-balancing, due to various impositions of stress on the work board. When the structure is in the non-service adjustment shown in Fig. 1, then, there would be no occasion for the same to tip or overbalance.

Should the occupant of the apartment desire to move, say to another apartment, the contents, together with any other contents, could be packed in both sections and the respective closures closed and fastened, as 120 shown in Fig. 1. Then, the sections would be folded to form a transporting chest, as shown in Fig. 7, and locked, as shown in Fig. 8, with any suitable fastening as indicated 125 at 43, 44 and 45.

It will now be clear that as the various closures have previously been closed and fastened, the contents cannot escape or become misplaced, during the operation of 130

5 folding the sections. It will also be clear, that after the sections have been locked into a folded adjustment, with the closures of the two sections in abutting relation, the contents of the two sections are not only separated but surreptitious access thereto would be doubly difficult.

10 With suitable handles 46, on the sides of one of the sections, it will be clear that the folded sections will pass the requirements of a trunk and can be handled as readily as the latter.

15 It is believed that the device of my invention will be fully understood from the foregoing description and while I have herein shown and described one specific form of my invention, I do not wish to be limited thereto except for such limitations as the claims may impart.

20 I claim:

1. In a combined folding cupboard and transporting chest, cupboard and chest sections of uniform height and width having open front faces and the former being superimposed, on and hinged to the latter whereby said sections may be folded with their open faces abutting to form a chest, a closure for said cupboard section hinged to swing downwardly about a horizontal axis

25 to form a work board when open, a closure 30 for said chest section hinged to swing about a vertical axis and having its lower edge co-acting with the floor when open to stabilize the structure and having its upper edge co-acting with said board to support the latter 35 in a work adjustment.

2. In a combined folding cupboard and transporting chest, cupboard and chest sections having open front faces and the former being superimposed on and hinged to the latter whereby said sections may be folded with their open faces abutting to form a chest, a closure for said cupboard section hinged to swing downwardly from a closure 40 adjustment about a horizontal axis to form a work board when open, closures for said chest section hinged to swing about vertical axes to coact with the floor and said work board closure, means on the inside of said chest closures for locking the latter to said 45 work board closure to support the latter in a work board position, and means on the outside of said chest closures for locking the latter in a chest closing position.

3. In testimony that I claim the foregoing as 50 my own, I hereby affix my signature.

TERESA M. WOOD.
